INSULATED TERMINAL

James P. Watson, Miami Shores, Fla. (59 Waterway Road, Waterway Village, Jupiter, Fla.), assignor of one-half to Joe Davidson, South Gate, Calif.

Filed Jan. 11, 1960, Ser. No. 1,537
6 Claims. (Cl. 339—198)

This invention relates to insulated terminals, and particularly terminals for the reception of conducting wires which may be spaced very close to each other without danger of voltage breakdown of insulation between adjacent terminals.

Certain characteristics of the terminal are similar to those of the terminal illustrated in U. S. Patent No. 2,882,515, Watson, to which reference is made for fuller understanding of this invention.

It is an object of this invention to provide an improved electric terminal for an electrical conductor.

It is a further object of this invention to provide an electric terminal which may be readily insulated from its surroundings.

It is a further object of this invention to provide an electric terminal adapted to be mounted in multiplicity on a terminal board, with a plurality of such terminals closely spaced together.

It is a further object of this invention to provide an electric terminal which is well suited to provide a passageway through a sealed barrier or wall, such as would be exemplified by the housing or casing of an electrical apparatus.

In accordance with these and other objects which will become apparent hereinafter, preferred forms of the present invention will now be described with reference to the drawings wherein:

FIG. 1 is a plan view illustrating a terminal block or member having a plurality of closely juxtaposed electric terminals or connectors arranged thereon in accordance with the present invention.

FIG. 2 is a cross-section taken on line 2—2 in FIG. 1.

FIG. 3 is an enlarged cross-section of a single connector or terminal.

FIG. 4 is a view similar to FIG. 3, illustrating a modified form of connector.

FIG. 5 is a fragmentary perspective view, illustrating a portion of the electric terminal of FIG. 3 at one stage in its fabrication, and

FIG. 6 is a fragmentary perspective view similar to FIG. 5, illustrating the modified form of FIG. 4.

Referring to the drawing, there is shown in FIG. 1 a terminal block or member 11 having a plurality of substantially parallel bores 12 therethrough. Residing in each bore 12 is a cylindrical insulating tube 13 passing through the block 11 and projecting therefrom at each side of the block, as shown at 14.

Within the insulating tube 13 is an elongate conducting member or terminal in the form of a conducting tube 16. The tube 16 projects at each end beyond the respective ends 14 of the cylindrical insulating sleeve 13, and the projecting portion is indented inwardly to form a helical groove 17, which encircles the tube once, as shown in FIG. 5. At each extended end of the tube 16, an axial groove or passageway 18 is cut through the wall of the tube. FIG. 5 shows the tube 16 in the process of fabrication after the helical indentation 17 has been formed. To complete fabrication of this conducting portion of the terminal, the tube is cut away as shown at 18' in FIG. 6, which illustrates a modified form of terminal. The extended axial groove shown at 18' is the same in both modifications of the invention.

At the other end of the helical indentation 17 the tube is indented inwardly, as shown at 19, to form a longi-

2

tudinal passageway, the outer walls of the passageway being completed by the insulating sleeve 13, as shown in FIG. 3. Also, as shown in FIG. 3, each end of the terminal or conducting tube 16 is substantially identical.

5 To use the terminal, a bendable conducting wire 21 is inserted into the longitudinal passageway 19, and then laid helically in the indentation 17, departing axially from the terminal by passing through the groove 18 and under the horn 32 (FIG. 6), residing in the hollow center portion of the tube 16, as shown at 22 in FIG. 3. To permit such wrapping of the wire 21 around the terminal 16, the conventional insulation 23 of the conductor is stripped back, as shown in FIG. 3.

A flexible insulating sleeve 24 is first slid over the 15 wire 21—23, and the sleeve is then extended over the end of the conducting tube 16, and then pressed over the projecting end of the cylindrical insulation 14, preferably abutting the mounting block or member 11. To secure the sleeve 24 in place, a strong but flexible ring 26, made preferably of plastic, is first slid over the wire 21—23 and then slid over the end of the insulating sleeve 24, where the sleeve encircles the cylindrical insulation 14.

The mounting member 11 may be either a terminal 25 block, as illustrated in FIG. 1, or may be a continuous wall, such as the housing or casing of a piece of electrical equipment, as indicated in FIG. 3. In FIGS. 1, 2 and 3, the mounting block 11 has been shown as being made of conducting material. Thus to separate one terminal 16 electrically from its fellow terminals, the cylindrical insulating tube 13 is required. However, when the mounting block 11 is itself an insulating member, as shown at 11' in FIG. 4, the insulating sleeve 13 may be omitted. To take its place at the projecting ends of the conducting terminal 16, however, a pair of cylindrical bosses 14', formed integral with the mounting block 11, are formed.

As in the FIG. 3 embodiment, the portion of the terminal 16' carrying the helical indentation 17' projects 40 even beyond these protuberant bosses 14', in order to allow the bendable conductor 21' to be inserted and wound around the terminal 16'.

The embodiment shown in FIG. 4 also illustrates a modified form of tube 16', wherein the inner end of the 45 wire 21' is accommodated inside the tube 16', as shown at 19', by forming a hole 31 at the inner end of the indentation 17', and communicating with the center 19' of the tube 16'. As in the case of the previous embodiment, the outer end of the terminal 16' is grooved longitudinally at 18' to form a horn 32 under which the wire 21' is tucked as it departs axially from the terminal 16'.

The modification illustrated in FIG. 4 also illustrates that the ring 26' may, if desired, be formed integral with the flexible insulating sleeve 24' at the end thereof.

55 As illustrated in FIG. 4, the center of the tube 16' is pinched together at 33 to form a dead end for the reception of the respective wires 21', which are pushed into the tube 16' from the opposite ends thereof. The pinching at 33 takes the place of the ends of the longitudinal indentations 19 of FIG. 3, which form stops for the wires in the FIG. 3 embodiment.

While the instant invention has been shown and described herein in what is conceived to be the most practical and preferred embodiments, it is recognized that 60 departures may be made therefrom within the scope of the invention which is therefore not to be limited to the details disclosed herein but is to be afforded the full scope of the claims.

What is claimed is:

70 1. Electrical connector comprising an elongate tubular conducting member having a helical indentation there-around terminating in a longitudinal groove communi-

cating with an end of said member, said member also having a longitudinal passageway communicating with the other end of said helical indentation, an insulating member circumjacent said conducting member and covering the same except for the portion having said helical indentation and said longitudinal groove, said longitudinal passageway, said helical indentation and said longitudinal groove being adapted to receive a bendable electric conductor which extends axially away from said conducting member, an insulating sleeve, said conducting member and insulating member being adapted to receive thereover said insulating sleeve, and a strengthening ring extending over the end of said insulating sleeve circumjacent said insulating member.

2. Electrical connection means comprising an elongate tubular conducting member having a helical indentation therearound terminating in a longitudinal groove communicating with an end of said member, said conducting member also having a longitudinal passageway communicating with the other end of said helical indentation, a cylindrical insulating member circumjacent said conducting member and covering the same except for the portion thereof having said helical indentation and said longitudinal groove, a bendable electric conductor residing in said passageway and indentation and extending axially away from said member through said groove, an insulating sleeve extending over said conducting member and over at least a portion of said insulating member, and a strengthening ring over the end of said insulating sleeve and circumjacent said insulating member.

3. Electric connection as claimed in claim 2 wherein said longitudinal passageway includes a longitudinal groove formed in said conducting member, the remaining portion of said passageway being formed by said insulating member.

4. Electric connection means comprising a mounting member, cylindrical insulation members projecting from said mounting member on each side thereof, a plurality of substantially parallel insulated bores through said cylindrical members and mounting member, elongate tubular electrically conductive terminal members disposed in said bores and projecting at each side of said mounting member beyond said cylindrical insulating members, each said tubular terminal member at each side of said mounting member having a helical indentation therearound in the portions projecting beyond said insulating members, and each of said tubular terminal members at each side of said mounting member further having a longitudinal groove communicating with said helical indentation at each extended end of said terminal member and a longitudinal passageway communicating with said helical indentation at the other end thereof, said helical indentation, said longitudinal passageway and said longitudinal groove being adapted to receive and secure a bendable electric conductor therein extending away from said terminal substantially axially thereof, an insulating sleeve, said tubular terminal member and said projecting insulating member being adapted to receive an insulating sleeve thereover, said clamping ring around the end of said insulating sleeve and circumjacent the projecting portion of said insulating member.

5. Electric connection means comprising a mounting member, cylindrical insulating members projecting from said mounting member on each side thereof, a plurality of substantially parallel insulated bores through said cylindrical insulating members and mounting member, elongate tubular conducting members disposed in said bores and projecting from said mounting member at each side thereof and beyond said insulating members, each of said tubular conducting members at each side of said mounting member having a helical indentation in the portion thereof projecting beyond said insulating member, and each of said tubular conducting members at each side of said mounting member further having a longitudinal passageway communicating axially with said helical indentation at the outer end of said helical indentation, and another longitudinal passageway communicating with said helical indentation at the other end thereof, a bendable electric conductor disposed and secured in said passageways and indentation and extending away from said tubular conducting member substantially axially thereof, an insulating sleeve over said conductor and tubular conducting member and projecting insulating member, and a clamping ring around the end of said insulating sleeve and circumjacent said insulating member.

6. Electrical connection as claimed in claim 5 wherein said longitudinal passageway comprises a cylindrical bore disposed on the axis of said elongate tubular conducting member.
